UNITED STATES PATENT OFFICE.

EDWARD E. KLEINSCHMIDT, OF CHICAGO, ILLINOIS, ASSIGNOR, BY MESNE ASSIGNMENTS, TO MORKRUM KLEINSCHMIDT CORPORATION, OF CHICAGO, ILLINOIS, A CORPORATION OF DELAWARE.

SELECTIVE SYSTEM AND APPARATUS.

Application filed December 21, 1922, Serial No. 608,341. Renewed May 5, 1928.

This invention relates to a system and apparatus for selectively controlling various operations from distant points, for example control of remote motors, switching apparatus and mechanical operations. It is particularly useful in the transmission of intelligence and in the preferred embodiment herein disclosed the invention is illustrated in its application to a printing telegraph system.

In selective systems of the kind referred to, where a plurality of distant operations must be controlled, transmitting and receiving apparatus are essential. Where the number of operations to be performed is greater than the number of channels for transmission of energy, as for example, where only one line wire is used in a printing telegraph system such as shown, a definitely timed relation of operation must be established between the transmitters and receivers. It will of course be understood by those skilled in the art, that the invention is not limited to use with a single line wire. A plurality of line wires may be used with the invention in its broader aspects, or the invention may obviously be adapted to signaling over single Morse channels of a multiplex system, or over a single carrier telegraph channel and it is applicable to the usual wireless or radio signalling systems.

Systems maintaining a substantially synchronous relation between distant apparatus are well known in the art. A particular class of such systems rely on operating the apparatus in definite cycles to maintain the necessary timed relation. Each cycle of operation comprises a starting of the apparatus at the beginning of the cycle, the performance of a series of operations, and the stopping of the apparatus at the end of the cycle. In the telegraph art such systems have become known as "start-stop" systems. The present invention is described and shown in its application to a system and apparatus of the start-stop type.

In the start-stop systems of the prior art, it has been the practice to operate the transmitting and receiving apparatus at slightly different speeds. This has been found necessary due to impossibility of avoiding slight variations in driving speed, and to enable proper correction to be made. Two general types of driving means have been used; the

usual motor drive timed to run at definite speeds in various manners; and stepping devices interrupting local direct current circuits. The Cardwell start-stop system and the "grasshopper" distributor systems are examples of the latter type. The usual motor driver systems are cumbersome, expensive and difficult to regulate. Ordinary stepping systems vary with changes in potential condition of contacts, and numerous other conditions and are therefore impractical. It is obvious that when the speeds of transmitter and receiver change more than a relatively slight degree, the operativeness of the system is completely destroyed until the speeds are readjusted. With transmitter and receiver at distant stations, the readjustment presents serious difficulties and results in annoyance and loss of time.

An object of the present invention is, to provide a system in which cumbersome and expensive motors are eliminated, and in which variations in speed potentials, contacts, and other local conditions are minimized. Another object is the provision of a simple system in which the transmitter and receiver are driven at substantially equal speeds, and in which no attention need be given to speed regulation. A further object is the production of a more efficient, reliable, less cumbersome and cheaper apparatus.

In general these objects are attained by utilizing ordinary locally generated commercial sources of alternating current to drive the transmitters and receivers in definitely timed relation with respect to the frequencies of such sources. The potentials and frequencies of such sources are standardized and closely regulated. All communities large enough to require telegraph service have such sources of alternating current for lighting and power purposes. The speed of operation of the apparatus in the present system is timed by these local sources and advantage is thereby derived from the close regulation customary on such power systems. For the details of the preferred form of invention, reference may be had to the following description and to the accompanying drawing of which

Fig. 1 is a plan view showing the essential elements of the transmitter.

Fig. 2 is a front elevation of the trans-

mitter with parts broken away to show the driving means.

Fig. 3 is a plan elevation showing essential elements of the receiver and control of an operating magnet.

Fig. 4 is an end elevation of the receiver with parts broken away to show the driving means and control of a selector mechanism.

Fig. 5 is a plan view of a modified form of receiver and driving means therefor.

Fig. 6 is an end elevation of the modified form with parts broken away to show the driving means and control of the selector.

Fig. 7 is a diagram showing a system wherein the invention is applied to a plurality of receivers and transmitters in the same circuit.

Transmitting apparatus.

Referring to Figure 1, numerals 1 to 6 denote a plurality of transversely movable permutation bars each bearing a plurality of cam surfaces 7. A plurality of letter or signal bars 8 are mounted to co-act with the signal bars 8 are mounted to co-act with the cam surfaces on bars 1 to 6, so that when the bars 8 are depressed, bars 1 to 6 are moved transversely in various combinations in accordance with a predetermined code as is well known in the art. Bar 6 is a universal bar and is moved transversely by the depression of each key or signal bar 8. As bar 6 moves transversely to the left on depression of a key, it engages pawl 9. Pawl 9 is moved forward by 6 and actuates bell crank 10, upon which 9 is pivotally mounted at 11. Bell crank 10 moves about its pivoted point 12 and closes contacts 13. As pawl 9 is moved to the left its cam surface 14 rides on fixed pin 15 and stresses spring 16. After contacts 13 have been closed the cam action of pin 15 on surface 14 moves pawl 9 about point 11 to release the pawl from actuating engagement with bar 6. In this manner, if a key is held depressed after the selective combination controlled thereby has been sent, contacts 13 will be free to open and a second character will not be sent. When the key is released pawl 9 and bell crank 10 will be returned to normal position under influence of the contact spring and spring 16. The usual keyboard interlock (not shown) may be provided to guard against release of a depressed key before the combination has been completely transmitted.

Closure of contacts 13 completes an energizing circuit from a locally generated source of alternating current, to coils 17 of a timed alternating current magnet. This magnet 60 comprises a permanent horseshoe magnet 18, to one leg of which is secured a U-shaped laminated soft iron core 19. Coils 17 are wound upon the legs 20 and 21 of core 19. Pivoted at 22 to the other leg of permanent magnet 18 is a soft iron armature 23.

When contacts 13 are open, a normal magnetic field is set up by 18, through core 19 and armature 20, tending to retain 20 in the position shown in Fig. 2. Legs 20 and 21 are cut at an angle and insure sticking of 70 the armature 23 in either of its biased positions. When contacts 13 are closed, reversals of current supplied to coils 17 alternately strengthen and weaken the normal magnetic field at legs 20 and 21, thereby causing oscillation of armature 23 about pivot 22 in unison with the reversals of the current supplied by the local alternating current source. Pivoted on 23 is a forked double acting pawl member 25. As the lower end of 23 moves to the right in Fig. 2, the upper branch of 25 pushes on a tooth of driving wheel 26 and the lower branch of 25 is moved from engagement with one tooth and rides over the next tooth on 26. On the return movement of 23, the lower branch of 25 pulls on the tooth it has ridden over, and the upper branch moves away from the tooth it pushed and rides over the next tooth. In this manner it will be apparent that wheel 26 is rotated in definite timed relation with respect to the reversals of alternating current. This timed relation may of course be varied as it depends on the throw of pawl 25 and the number of teeth and size of toothed wheel 26. These are varied to adapt the transmitter to the particular local conditions and speed requirements. It will therefore be obvious that two stations on the same system need not necessarily have the same frequency of alternating current supply. For example a transmitter on 60 cycle supply may be driven to send impulses at the same rate as a transmitter on a 25 cycle supply. For the sake 105 of uniformity in apparatus, the same frequency of alternating current at different stations is to be preferred.

Mounted in bearings, or supports (not shown) so as to be rotatably and axially movable, is a pin barrel 27. Toothed wheel 26 is rigidly fastened to, and rotates, barrel 27. Mounted on barrel 27 in angularly and axially displaced relation to each is a series of pins 28 to 34. Barrel 27 is normally held in retracted axial position by a contact member 35 through the action of spring 36. Line contacts 37 are normally closed with 115 27 in retracted position. In normal resting position of the pin barrel, pin 28 engages a latch member 38 and prevents locking of contacts 13.

When as above described, contacts 13 have been closed by actuation of bar 6, armature 23 commences to vibrate in unison with the alternating current reversals and rotates the pin barrel, on the first step, 28 moves out of engagement with 38 which then locks contacts 13 in closed position. Pin 29 then engages a fixed cam member 39. This 120 125

causes axial movement of the pin barrel and thereby opens contacts 37 causing a preliminary or start condition on the line. After 29 has passed cam 39, barrel 27 is axially 5 restored through action of spring 36, and contacts 37 are again closed. The pin barrel continues to rotate and pins 30 to 34 successively pass by cam members 40 to 44 carried by bars 1 to 5. As shown in Fig. 10 bars 2, 4 and 5 are actuated and in this condition interpose cams 41, 43 and 44 respectively in the paths of pins 31, 33 and 34. As each pin passes a corresponding actuated bar (1 to 5) an axial movement of 15 the pin barrel will be caused, actuating contacts 37 to send code combinations of marking and spacing conditions on the line or transmitting medium. It will be obvious that the relative times occupied by marking, spacing start, and stop condition may 20 be varied at will by increasing or decreasing the width of cams 39 to 44 and varying proportions to suit varying line conditions. Block signals or separated interval signals 25 may obviously be sent depending on proportions of the parts. Reversed polarity impulses may also be used if desired, in obvious manner. After the last impulse of a combination has been sent contacts 37 remain closed, and the pin barrel rotates 30 under control of the local alternating current source until pin 28 engages latch 38 and releases contacts 13. Even if the key is held depressed contacts 13 will open, rotation 35 of the pin barrel will stop, and the key must be released to permit re-engagement of bar 6 and pawl 9 before another code combination can be sent. It will of course be understood that the parts are shown in schematic form and distorted relation to better 40 illustrate the invention. For the sake of clearness supports have been omitted and only so much of well known apparatus has been illustrated as is required to clearly 45 show the invention.

Receiving apparatus.

In the preferred embodiment of receiving apparatus shown in Figs. 3 and 4, a motor 50 of the same type has been shown as is used in the transmitter. This need therefore not be here described, but for convenience the same numerals with 100 added thereto have been used to designate like parts. The local 55 alternating current source need not be of the same frequency as that at the transmitter, as above pointed out, but this is preferable.

Incoming code combinations of electrical 60 impulses operate line magnet 150 to actuate armature 152 about a pivotal point, under influence of spring 153, in obvious manner. Movement of 152 (as shown in Fig. 3) caused by a starting line condition, permits pin barrel 154 to move axially to the

right under influence of member 155 and spring 156, moving pin 157 and permitting contacts 113 to close the local alternating current circuit. Pin barrel 154 then rotates under the influence of the local alternating current source in definitely timed relation with respect to the change of line conditions caused by the transmitter. As the barrel rotates, pins 158 to 162 successively pass trips 163 to 167. If a marking condition exists on the line as a pin passes its trip, axial movement of the pin barrel will be permitted by 150 and the respective pin is caused to align with and actuate its respective trip. If a spacing condition exists 70 on the line as a pin passes the trip, no axial movement of the barrel will be permitted and the trip will be unactuated. The rotation of the pin barrel 154 is so timed that bars 1 to 5 (Fig. 1) of the transmitter will 75 cause marking or spacing conditions which control the actuation of trips 163 to 167 respectively. With bars 2, 4 and 5 actuated, trips 164, 166 and 167 will be set. As trips 163 to 167 are set latches 168 individual 80 to each trip operate to retain the set trips in actuated position. Trips 163 to 167 control a plurality of the movable slotted selector bars 169. The selector bars 169 control a plurality of actuating bars 170 which 85 in turn control the desired selective operation. A selector of this type is fully disclosed in copending application Serial Number 588,668, filed September 16, 1922, to which reference may be had for details of the selector and mechanism controlled thereby. Only 90 so much of the selector mechanism is here shown as will enable a complete understanding of the invention to be had in its specific application to the selector disclosed in Serial Number 588,668. It should, however, be understood, that the present invention is useful 95 in other relations.

After a selective combination has been completely received pin 157 closes contacts 171 and completes an energizing circuit for operating magnet 172. Magnet 172 supplies or controls the actuating energy for completing a selected operation. In the apparatus shown 172 operates 173 which in turn completes the operation of a selected actuating bar 170. The selector mechanism may control a printing telegraph machine of the types shown in my co-pending applications Serial Number 390,598 filed June 1, 1920; 115 Serial Numbers 530,880, filed June 21, 1922, and 576,362 filed July 20, 1922, in which case, bars 170 would actuate the type-bars, and magnet 172 would be the printer magnet.

Figs. 5 and 6 illustrate a modified form of driving means for a receiving apparatus similar to that shown in Figs. 3 and 4.

It will be unnecessary to describe in detail the operation and only so much as has been 120 130

modified will be described. Selective code combinations cause the closure of contacts 213 as above described. Armature 276 of alternating current magnet 275 oscillates in unison with the local current reversals. The oscillations of 276 permit step by step rotation of pin barrel 254 in properly timed relation with respect to the incoming signals, as above set forth. Driving energy is supplied to the pin barrel by means of energy stored in spring 278 through loosely mounted gear 279 and pinion 280. On each energization of operating magnet 272, operating frame 273 moves forward and permits member 282 to be rotated on pivot 283, by the action of spring 284. Pivotaly mounted on member 282 is spring pressed pawl 285, which as 282 rotates, operates on ratchet wheel 286 to wind spring 278. Retaining pawl 287 prevents release of 278 on de-energization of 272. In this manner energy is stored in spring 278 on each operation of magnet 272, to effect the succeeding rotation of pin barrel 254. Parts similar to those shown in Figs. 3 and 4 are indicated by the same numerals with 100 added thereto.

The system.

A system disclosing a plurality of transmitters and receivers on a single circuit is disclosed in Fig. 7. It will be apparent that the sole timing means is the regulation afforded by commercial alternating current sources local to the apparatus. Apparatus is driven at substantially equal speeds all along the line. The transmitters and receivers are not adapted for general use with common apparatus of the prior art owing to the method of timing. The invention must be applied to prior art apparatus before they can be used in the system. Receivers and transmitters herein disclosed are therefore peculiar to the system.

Plainly the inventions are not limited to the specific embodiments shown and described herein, but are to be limited only by the following claims.

What is claimed is:

1. In a selective system including transmitting apparatus adapted to transmit code combinations of electrical impulses, and receiving apparatus selectively controlled by said impulses; the method of maintaining a fixed time relation between said apparatus which consists in utilizing alternating current sources local to said apparatus as the sole speed regulating means for said apparatus.

2. In a selective system, transmitting apparatus operable to transmit selective combinations of electrical impulses, sources of alternating current local to said transmitting apparatus constituting the sole speed regulating agencies for said transmitting appa-

ratus, receiving apparatus controlled by said transmitting apparatus, and sources of alternating current local to said receiving apparatus constituting the sole speed regulating agencies for maintaining said receiving apparatus in fixed time relation of operation with respect to said transmitting apparatus.

3. In a selective system, plurality of transmitters adapted to transmit selective combinations of electrical impulses; sources of alternating current individual to said transmitters constituting the sole agencies for timing the speed of transmission of said impulses; a plurality of receivers responsive to said impulses and sources of alternating current individual to said receivers constituting the sole speed regulating agencies for timing the speed of operation of said receivers.

4. In a selective system, a plurality of transmitting stations; transmitting apparatus at said transmitting stations adapted to transmit selective combinations of electrical impulses; sources of alternating current local to said stations constituting the sole agencies for timing the speed of operation of said transmitting apparatus, a plurality of receiving stations; receiving apparatus at said receiving stations controlled by said transmitted impulses, and sources of alternating current local to said receiving stations constituting the sole agencies for timing the speed of operation of said receiving apparatus.

5. In a selective signalling system, a plurality of transmitting stations; transmitters individual to said transmitting stations embodying distributors of electrical impulses, sources of alternating current local to said stations constituting the sole agencies for regulating the speed of operation of said transmitters; a plurality of receiving stations; receivers individual to said receiving stations embodying distributors operable in separate cycles to receive said impulses; and sources of alternating current local to said receiving stations constituting the sole agencies for regulating the speed of operation of said distributors.

6. In a selective signalling system, a plurality of transmitting stations; transmitting apparatus at said transmitting stations adapted to transmit selective combinations of electrical impulses, said transmitting apparatus embodying rotary distributors started into rotation to transmit said impulses and arrested in rotation at the end of each revolution after a selective combination has been transmitted; sources of alternating current local to said transmitting stations constituting the sole agency for timing the speed of rotation of said distributors; a plurality of receiving stations; receiving appa-

ratus at said receiving stations, said receiving apparatus embodying a plurality of rotary distributors started into rotation to receive said impulses and arrested in rotation 5 at the end of each revolution after said selective combination has been received; and sources of alternating current local to said receiving stations constituting the sole agencies for timing the speed of rotation of 10 said receiving distributors.

7. In a selective signalling system, a movable distributor; and a source of alternating current controlling said distributor and controlled by said distributor, the frequency of 15 said alternating current being timed independently of said distributor.

8. In a selective signalling system, a rotary distributor; and a source of alternating current controlling said distributor and controlled by said distributor, the frequency of 20 said alternating current being timed independently of said distributor.

9. In a selective signalling system, a distributor movable in cycles, a source of alternating current timed in frequency independently 25 of said distributor; and electro-responsive means actuated by current supplied by said source and causing said distributor to be rotated in fixed time relation with respect 30 to reversals of said current.

10. In a selective system, a rotary distributor; a source of alternating current timed in frequency independently of said distributor; and electro-responsive means 35 energized by reversals of current supplied by said source and driving said distributor in fixed time relation with respect to said reversals of current.

11. In a selective signalling system, a distributor movable in cycles, and arrested in motion at the end of each cycle; an independently timed local source of alternating current; and electro-responsive means actuated by current supplied by said source and 45 causing said distributor to be rotated in fixed time relation with respect to reversals of said current.

12. In a selective system, a rotary distributor; arrested in motion at the end of 50 each revolution; an independently timed local source of alternating current; and electro-responsive means energized by reversals of current supplied by said source and driving said distributor in fixed time relation with respect to said reversals of current.

13. In a selective system, a rotary distributor electro-responsive means controlling said distributor, a circuit controlling said electro-responsive means; contacts controlling said circuit; means for initially closing said contacts to start rotation of said distributor and means controlled by said distributor for maintaining said contacts closed until a revolution has been completed by 65 said distributor, thereby causing said dis-

tributor to be arrested in motion at the end of said revolution.

14. In a selective system, a selector mechanism, a movable member co-acting with said selector mechanism to cause selected operations to be performed; and an alternating current motor actuated by a local independently timed alternating current controlling said movable member, said motor comprising an oscillating member, a plurality of coils, controlling said oscillating member, and a normally magnetized core for said coils. 70

15. In a selective system, a selector mechanism, a rotary distributor co-acting with said selector mechanism to cause selected operations to be performed; and an alternating current motor actuated by a local independently timed alternating current driving said distributor; said motor comprising a normally magnetized core, a plurality of coils carried by said core, and an oscillating pawl carrying member controlled by said coils and rotating said distributor. 80

16. In a selective signalling system, a receiving apparatus selectively controlled by incoming selective combinations of electrical impulses, and a source of alternating current local to said receiving apparatus constituting the sole agency for timing the speed of operation of said apparatus with respect 90 to said incoming impulses. 95

17. In a selective signalling system, a receiving apparatus controlled by incoming 100 selective combinations of electrical impulses; said receiving apparatus embodying a distributor operable in cycles; and a source of alternating current local to said receiving apparatus constituting the sole agency for 105 timing the speed of operation of said distributor with relation to said incoming impulses.

18. In a selective signalling system, a receiving apparatus controlled by incoming 110 selective combinations of electrical impulses, said receiving apparatus embodying a rotary distributor started into rotation to receive said impulses, and arrested in rotation at the end of each revolution after a selective combination has been received; and a source of alternating current local to said receiving apparatus constituting the sole agency for timing the speed of rotation of 115 said distributor. 120

19. In a selective system, a selecting mechanism, a rotary distributor, an alternating current source controlled by said rotary distributor and timed in frequency independently of said distributor, means responsive to incoming code combinations of electrical impulses co-acting with said distributor to control said selector mechanism, and means responsive to said alternating current source controlling said distributor 125 130

to maintain a definite timed relation of movement of said distributor with respect to said incoming impulses.

20. In a selective system, a movable distributor; electro-responsive means controlled by incoming code combinations of electrical impulses and controlling said distributor; a source of alternating current controlled by said distributor and timed in frequency independently of said distributor; and means responsive to said source for maintaining movement of said distributor in fixed timed relation with respect to said incoming impulses.
- 15 21. In a selective system, a rotary distributor; electro-responsive means controlled by incoming code combinations of electrical impulses and controlling said distributor; a source of alternating current controlled by said distributor and timed in frequency independently of said distributor; and means responsive to said source for maintaining movement of said distributor in fixed timed relation with respect to said incoming impulses.

- 25 22. In a selective system, a distributor movable in cycles; electro-responsive means controlled by incoming code combinations of electrical impulses initiating a cycle of movement of said distributor; a source of alternating current controlling the cyclic movement of said distributor in definite timed relation with said incoming impulses; and means controlled by said distributor and controlling said source to arrest movement of said distributor at the end of a cycle.

- 30 23. In a selective system, a rotary distributor movable in cycles; electro-responsive means controlled by incoming code combinations of electrical impulses initiating a cycle of movement of said distributor; a source of alternating current controlling the cyclic movement of said distributor in definite timed relation with said incoming impulses; and means controlled by said distributor and controlling said source to arrest movement of said distributor at the end of a cycle.

- 35 24. In a selective system, a rotary distributor movable in cycles; electro-responsive means controlled by incoming code combinations of electrical impulses initiating a cycle of movement of and controlling said distributor; a source of alternating current;

- 40 50 rent; electro-responsive means vibrating in unison with reversals of current generated by said source maintaining cyclic movement of said distributor in timed relation with respect to said impulses; and means controlled by said distributor controlling said source to arrest movement of said distributor at the end of a cycle.

- 45 55 60 65 25. In a selective system, a rotary distributor movable in cycles; a magnet controlled by incoming code combinations of

electrical impulses initiating a cycle of movement of said distributor; a source of alternating current; a magnet vibrating in unison with reversals of current generated by said source causing cyclic movement of said distributor in definite timed relation with respect to said impulses; and contact mechanism actuated by said distributor and controlling said source to arrest movement of said distributor at the end of a cycle.

75 26. In a selective system, a distributor movable in cycles; electro-responsive means controlled by incoming code combinations of electrical impulses initiating a cycle of movement of and controlling said distributor; a source of alternating current; electro-responsive means actuated by reversals of current generated by said source; a stepping mechanism actuated by said last mentioned means and controlling movement of said distributor in fixed timed relation with respect to said incoming impulses; and a contact mechanism actuated by said distributor and controlling said last mentioned means to arrest movement of said distributor at the end of a cycle.

80 27. In selective system, a rotary distributor movable in cycles; electro-responsive means controlled by incoming code combinations of electrical impulses initiating a cycle of movement of and controlling said distributor; a source of alternating current; electro-responsive means actuated by reversals of current generated by said source; a stepping mechanism actuated by said last mentioned means and actuating movement of said distributor in fixed timed relation with respect to said incoming impulses; and a contact mechanism actuated by said distributor and controlling said last mentioned means to arrest movement of said distributor at the end of a cycle.

85 90 95 100 105 110 115 120 28. In a selective system, a selecting mechanism, a movable distributor controlling said selecting mechanism, actuating means for said distributor, and means responsive to code combinations of electrical impulses cooperating with said distributor to control said selecting mechanism; said actuating means being under control of movement in one direction of said distributor, and said selecting mechanism being under control of movement in another direction of said distributor.

125 29. In a selective system, a rotatory and axially movable distributor; means responsive to code combinations of electrical impulses controlling said distributor; means controlling rotation of said distributor and controlled by axial movement thereof; and selecting mechanism controlled by rotary movement of said distributor.

130 30. In a selective system, a rotary and axially movable distributor; means responsive to code combinations of electrical impulses

controlling said distributor; actuating means adapted to rotate said distributor and controlled by axial movement thereof; and selecting mechanism controlled by rotary movement of said distributor.

31. In a selective system, a rotary and axially movable distributor; means responsive to incoming code combinations of electrical impulses controlling said distributor; a source of alternating current; electro-responsive means actuated in fixed timed relation with respect to said incoming impulses by reversal of current generated by said source; a stepping mechanism actuated by said electro-responsive means controlling rotation of said distributor; and a contact mechanism controlled by axial movement of said distributor and controlling said source.

32. In a selective system, a rotary and axially movable distributor; means responsive to incoming code combinations of electrical impulses controlling said distributor; and contact mechanism controlled by axial movement of said distributor.

33. In a selective system, a rotary and axially movable distributor; means responsive to incoming code combinations of electrical impulses controlling said distributor; and contact mechanism actuated and controlled by combined axial and rotary movement of said distributor.

34. In a selective system, a rotary and axially movable distributor; means responsive to incoming code combinations of electrical impulses controlling said distributor; a source of alternating current; electro-responsive means actuated in fixed timed relation with respect to said incoming impulses by reversal of current generated by said source; a stepping mechanism actuated by said electro-responsive means rotating said distributor; and a contact mechanism controlled by axial movement of said distributor and controlling said source.

35. In a selective system, a movable distributor; means responsive to incoming code combinations of electrical impulses controlling said distributor; a source of alternating current local to said distributor; an electro-magnet including a permanently magnetized core and controlled by reversals of current derived from said source; an armature for said electro-magnet vibrating in timed relation with said current reversals; and a stepping mechanism actuated by said armature to actuate said distributor in timed relation with respect to said incoming impulses.

36. In a selective system, a movable distributor; means responsive to incoming code combinations of electrical impulses controlling said distributor; a source of alternating current local to said distributor; an electro-magnet including a permanently magnetized core and controlled by reversals of current derived from said source; an ar-

mature for said electro-magnet vibrating in timed relation with said current reversals; a stepping mechanism actuated by said armature to actuate said distributor in timed relation with respect to said incoming impulses; and a contact mechanism controlling said source actuated by said distributor.

37. In a selective system, a movable distributor; means responsive to incoming code combinations of electrical impulses controlling said distributor; a source of alternating current local to said distributor; an electro-magnet actuated by current reversals generated by said source; an armature for said electro-magnet vibrating in timed relation with said current reversals; a double acting pawl controlled by said armature; and a ratchet member stepped by said pawl on each movement of said armature to step said distributor.

38. In a selective system, a rotary distributor; means responsive to incoming code combinations of electrical impulses controlling said distributor; a source of alternating current local to said distributor; an electro-magnet actuated by current reversals generated by said source; an armature for said electro-magnet vibrating in timed relation with said current reversals; a double acting pawl controlled by said armature; a ratchet member stepped by said pawl on each movement of said armature to rotate said distributor in definite timed relation with respect to said impulses; and a contact mechanism controlling said source actuated by said distributor.

39. In a printing telegraph system, a movable distributor; electro-responsive means controlled by incoming code combinations of electrical impulses controlling said distributor; selecting mechanism controlled by said distributor; printing mechanism controlled by said selecting mechanism; a source of alternating current controlled by said distributor; means responsive to said source of alternating current maintaining a definite timed relation of movement of said distributor with respect to said impulses; and operating means for said printing means controlled by said distributor.

40. In a printing telegraph system, a rotary distributor; electro-responsive means controlled by incoming code combinations of electrical impulses controlling said distributor; selecting mechanism controlled by said distributor; printing mechanism controlled by said selecting mechanism; a source of alternating current controlled by said distributor; means responsive to said source of alternating current maintaining a definite timed relation of movement of said distributor with respect to said impulses; and operating means for said printing means controlled by said distributor.

41. In a printing telegraph system, a dis-

- tributor movable in cycles; electro-responsive means controlled by incoming code combinations of electrical impulses initiating a cycle of said distributor; a source of alternating current controlling the cyclic movement of said distributor in fixed timed relation with respect to said incoming impulses; a selecting mechanism controlled by said distributor; a printing mechanism controlled by said selecting mechanism; operating means for said printing mechanism controlled by said distributor; and means controlled by said distributor controlling said source to arrest movement of said distributor at the end of a cycle.
42. In a printing telegraph system, a rotary distributor movable in cycles; electro-responsive means controlled by incoming code combinations of electrical impulses initiating a cycle of said distributor; a source of alternating current controlling the cyclic movement of said distributor in fixed timed relation with respect to said incoming impulses; a selecting mechanism controlled by said distributor; a printing mechanism controlled by said selecting mechanism; operating means for said printing mechanism controlled by said distributor; and means controlled by said distributor controlling said source to arrest movement of said distributor at the end of a cycle.
43. In a printing telegraph system, a rotary start-stop distributor; a selecting mechanism controlled during a single revolution of said distributor to select a character; a printing mechanism controlled by said selecting mechanism; electro-responsive means controlled by code combinations of electrical impulses to initiate a revolution of said distributor and controlling said selecting mechanism to select a character; a source of alternating current; electro-responsive means vibrating in unison with reversals of current generated by said source to drive said distributor in definite timed relation to said impulses received by said first mentioned electro-responsive means; means controlled by said distributor to operate said printing mechanism, and means controlled by said distributor controlling said source to arrest movement of said distributor at the end of a revolution.
44. In a selective system, electro-magnetic means responsive to incoming combinations of electrical impulses; a movable distributor started in operation by said electro-magnetic means and continuing in definite timed operation with respect to said incoming impulses under control of an independent source of alternating current local to said distributor, and means controlled by said distributor to stop operation thereof when a complete combination of impulses has been received.
45. In a printing telegraph receiver, a distributor, a tension spring for supplying energy to rotate said distributor and means for maintaining the tension of said spring between predetermined values.
46. In a printing telegraph receiver, a rotating shaft, a tension spring for supplying energy to rotate said shaft, and means including a second spring for maintaining the tension of said spring between pre-determined values.
47. In a printing telegraph receiver, a rotatable shaft axially operable in response to a received code combination of impulses, a tension spring for supplying energy to rotate said shaft, an electro-magnetic means, and means including a second spring controlled by said electro-magnetic means for maintaining the tension of said spring between pre-determined values.
48. In a printing telegraph receiver, a rotatable shaft, axially operable in response to received code combinations of impulses, a tension spring for supplying energy to rotate said shaft, an electro-magnet, a mechanical connection between said spring and said electro-magnet, and a second spring controlled by said magnet for operating said mechanical connection whereby energy is transmitted to said first mentioned spring.
49. In a printing telegraph receiver, a rotatable shaft axially operable in response to a received code combination of impulses, a tension spring for supplying energy to rotate said shaft, an electro-magnet and a second spring for supplying energy to said first spring under control of said magnet.
50. In a printing telegraph receiver, a rotatable shaft axially operable in response to received code combinations of impulses, a tension spring for supplying energy to rotate said shaft, an electromagnet, a second spring tensioned by said magnet, and means for transmitting the energy in said second spring to said first spring.
51. In a printing telegraph receiver, a rotatable shaft axially operable in response to received code combinations of impulses, a tension spring for supplying energy to rotate said shaft, an electrical source of energy, a second spring tensioned by said source of energy, and means for transmitting the energy in said second spring to said first spring, said transmission of energy being controlled by said electrical means.
52. In a printing telegraph receiver, a rotatable shaft axially operable in response to received code combinations of impulses, a tension spring for supplying energy to rotate said shaft, a source of energy, a second spring tensioned by said source of energy and means for transmitting the energy in said second spring to said first spring, the rate of transmission of said energy being controlled by said source of energy.
53. In a printing telegraph receiver, a ro-

- tatable shaft axially operable in response to received code combinations of impulses, a tension means for supplying energy to rotate said shaft, a source of energy, a second tension means, a lever controlled by said source of energy for transmitting energy to said second tension means, said lever being operated by said second tension means for transmitting its energy to said first mentioned tension means. 5
54. In a printing telegraph receiver, a rotatable shaft axially operable in response to received code combinations of impulses, a tension means for supplying energy to rotate said shaft, a source of energy, a second tension means, and a lever controlled by said source of energy and said second tension means for transmitting energy to said first mentioned tension means. 10
55. In a printing telegraph receiver, a rotatable selector shaft and a spring member for rotating said shaft. 15
56. In a printing telegraph receiver, a rotatable selector shaft, a spring member for rotating said shaft, a signalling line and means controlled by the received impulses over said signalling line for maintaining said spring member at a predetermined tension to rotate said shaft. 20
57. In a printing telegraph receiver, a rotatable selector shaft, tension means for providing energy to rotate said shaft and means for controlling the rate of transmission of energy from said tension device to said shaft. 25
58. In a printing telegraph receiver, a rotatable selector shaft, tension means for providing energy to rotate said shaft, a signalling line, means controlled by impulses received over said line for supplying energy to said tension member, and means for controlling the rate of rotation of said shaft. 30
59. In a printing telegraph receiver, a rotatable selector shaft, a member for rotat-
- ing said shaft, and means responsive to received impulses for maintaining said spring member tensioned. 35
60. In a printing telegraph receiver, a rotatable selector shaft, a spring member for rotating said shaft, means responsive to received code combinations of impulses for selectively operating said shaft to select a pre-determined character for operation and means responsive to said received impulses for maintaining said spring member in tension. 40
61. In a selective system, a group of stations, selecting devices located at each station, electrical connections between said stations, means to transmit signals over said electrical connections to control said selecting devices, means responsive to said signals for selectively operating said devices, means for driving and timing the speed of operation of said selectors comprising a continuous operating source of alternating current individual to each station, said sources of alternating currents remaining at substantially fixed frequency relation with respect to each other. 45
62. In a selector system, a plurality of stations, rotatable selecting apparatus at each station, a signalling line connected to said stations, means for transmitting signals over said signalling line, means responsive to said signals for variably operating said selector apparatus and means responsive to a continuously operating source of alternating current individual to each station, for driving the selecting apparatus thereof at a predetermined speed and acting jointly with each of said sources of alternating current for maintaining said selectors in synchronism. 50
